UNITED STATES PATENT OFFICE.

GEORGE J. KEPPLINGER, OF DWIGHT, ILLINOIS.

FLOOR PLANER AND SCRAPER.

No. 903,868.

Specification of Letters Patent.

Patented Nov. 17, 1908.

Application filed March 27, 1908. Serial No. 423,768.

To all whom it may concern:

Be it known that I, GEORGE J. KEPPLINGER, a citizen of the United States, residing at Dwight, in the county of Livingston and State of Illinois, have invented a new and useful Floor Planer and Scraper, of which the following is a specification.

This invention relates to an implement for planing and scraping floors; and has for its object to provide a tool which shall be strong and simple in construction and capable by its own weight of holding the planing bit or scraping blade to its work.

Another object of invention pertains to the manner of mounting the holder for the planing bit and scraping blade in the tool frame whereby it may be quickly changed from an inclined to a substantially vertical position to enable the tool to be operated respectively as a floor planer or scraper.

With these and other objects in view the invention consists of the novel construction combination and arrangement of parts hereinafter described and claimed and illustrated in the accompanying drawing in which—

Figure 1 is a perspective view of the improved planer and scraper; Fig. 2 a longitudinal sectional view of the same adjusted as a planer; Fig. 3 a transverse sectional view in the line 3—3 of Fig. 2; Fig. 4 a longitudinal sectional view of the bit holder on the line 4—4 of Fig. 3 arranged as a scraper, looking in the direction of the arrows, and Fig. 5 a view of a detail of construction.

Similar reference numerals are used for the same parts in all the figures.

In the drawing the numeral 1 indicates a heavy rectangular open frame, made preferably of cast iron, with parallel side walls 2 and 3 and a rear wall 4 having vertically disposed outer and inner faces when in position on the floor, and a front wall 5, the faces of which incline in opposite directions from the top to the wider bottom. The intermediate portion of the bottom of the sides 2 and 3 are parallel to the top of the frame but incline slightly upward at their front and rear ends to prevent contact with the floor when the tool is in operation.

The rear end of the frame 1 is supported at each side on a wheel 6 mounted on a bolt 7 passing through the respective side walls of the frame and held by a nut. The peripheries of the wheels extend a slight distance below the bottom of the frame to pre-

vent the latter dragging on the floor when the tool is pushed or pulled thereover.

Within the frame 1 is placed the holder 8 for the planer bit and scraper blade and comprises two parallel side bars 9 and 10 cross connected at the top by bar 11 and at its lower end by a plate 12. These parts are preferably cast integral but they may be built up if desired. The side bar 10 has a rearwardly extending lug or projection 13 near its lower end provided with a threaded opening for a fastening bolt 14 which extends through a vertical slot 15 in the side wall 3 of the frame 1. A nut 16 threaded on the bolt 14 outside the frame secures the holder in fixed position when tightened, and when loosened, the position of the holder under certain conditions hereinafter described may be changed. The side bar 9 of the holder has an angular notch 9^a in its rear face, opposite the bolt hole in the lug or projection 13, in which notch is seated the head of a bolt 17 for supporting the holder 8 on that side of the tool. The bolt 17 extends through a vertical slot 18 in the side 70 wall 3 of the frame 1 and is held immovable by a nut 19 on the outside of the frame and opposite the nut 16.

The numeral 20 indicates the plane bit or iron, the lower end of its rear side bearing 85 against the cross plate 12 of the holder 8 and clamped to said holder by a front plate 21 and bolts 22 passing through slots 23 in the ends of plate 21 and into the side bars 2 and 3. On tightening these bolts the plate 90 21 presses the bit 20 against the holder and prevents the bit being moved. When the bit 20 is to be raised or lowered in the holder, this movement is accomplished by means of a screw stem 24 extending through a longitudinally disposed threaded socket 25 on the top cross bar 11 of said holder and swiveled in a coupling 26 connected to the upper end of the bit. The screw stem 24 is provided on its upper end with a hand wheel 27 or other means for turning it, while its lower end is journaled in the upper end of the coupling 26 and retained in rotatable connection therewith by a yoke shaped key 28 fitted into a slot in the coupling, the legs 29 100 of said key straddling a reduced neck 30 on the lower end of said screw stem. The upper end of the bit 20 extends between fingers 31 on the coupling and is detachably fastened thereto by a pin 32. 110

A housing 35 projects upwardly from the frame side 2 in which is formed a transverse horizontal slot 36 for a bolt 37 having a head 38 on its inner end and threaded on its outer end for a nut 39 by means of which the bolt may be secured at any point in the length of the slot. A short pin 40 projects from the bolt head 38 into a longitudinal groove 41 made in the edge of the blade holder 8.

10 The tool is operated by a handle 33 bolted to the sides of the frame near the front and extends rearwardly at an upward inclination to such height as to be grasped by a person standing erect. A brace 34 is fastened to 15 the rear wall of the frame and to the handle to give it steadiness and rigidity.

When the tool is to be used as a floor planer, the holder is set at an angle as shown in Figs. 1 and 2 and pushed over the floor, 20 its weight holding the bit to its work, but when a floor is to be scraped, the bit is removed by loosening the clamping plate and disengaging the coupling 26 by removing the pin 32. A scraping blade is then inserted 25 in the holder, and the latter adjusted to vertical position, see Fig. 4, by loosening the nuts on bolts 14, 17 and 37. The holder when changed to an erect position raises the bolt 14 and causes the bolt 37 to move forward hence the necessity for the slots 15 and 30 18. After the holder has been fastened by tightening the nuts on the aforesaid bolts, the bolt 17 is raised in its slot until its head is seated in the notch 9^a, the nut is then 35 tightened and after adjusting the edge of the blade the tool is ready for use as a scraper.

What is claimed is:—

1. In a floor planer and scraper, a wheeled 40 frame having a plurality of bolt receiving slots, a planing or scraping blade carrier mounted within the frame and adjustable to varying angular positions, bolts extending through the slots and serving to lock said 45 carrier in adjusted position, the bolts serving also as fulcrums on which the carrier may be tiltably adjusted, and an auxiliary locking bolt extending through one of the

frame slots and serving to engage and hold the carrier in adjusted position. 50

2. In a floor planer and scraper, an open frame having supporting wheels said frame being provided with vertical and horizontal slots, a planing or scraping blade carrier mounted within the frame and having an elongated groove 55 at one side, locking bolts extending through the vertical slots of the frame and forming carrier supports, and an auxiliary bolt extending through the horizontal slot of the frame and having its inner end engaging in the groove of the carrier.

3. In a floor planer and scraper, an open frame having supporting wheels and provided with vertical and horizontal slots, a planing or scraping blade carrier, bolts 65 extending through the vertical slots of the frame and engaging said carrier, the carrier having an angular recess for the reception of the head of one of the said bolts, and one of the side walls of the carrier being provided with an elongated groove, and a locking bolt 70 extending through the horizontal slot of the frame and entering said groove. 75

4. In a floor planer and scraper, a wheeled frame having vertical and horizontal slots, a 80 blade carrier mounted in the frame and having at one side a perforated ear, a bolt extending through the ear and one of the vertical slots said carrier being provided at its opposite side with an angular recess in alignment with the ear, a second bolt extending through another of the vertical slots and having its head fitting within said angular recess the side wall of the carrier being provided with an elongated groove, an auxiliary 85 bolt extending through the horizontal slot and entering said groove, and a blade adjusting means on said carrier.

In testimony that I claim the foregoing as my own, I have hereto affixed my signature in the presence of two witnesses. 90

GEORGE J. KEPPLINGER.
